UNITED STATES PATENT OFFICE.

WALTER L. HENDRICKS, OF AURORA, ILLINOIS.

HARVESTING MACHINE.

1,344,130.

Specification of Letters Patent. Patented June 22, 1920.

Application filed March 15, 1918. Serial No. 222,596.

To all whom it may concern:

Be it known that I, WALTER L. HENDRICKS, a citizen of the United States, and resident of Aurora, county of Kane, and 5 State of Illinois, have invented certain new and useful Improvements in Harvesting Machines, of which the following is a specification, and which are illustrated in the accompanying drawings, forming a part 10 thereof.

The invention relates to harvesting machines, and particularly to the class of machines known as reapers and binders wherein the standing grain is cut by a so-called 15 sickle bar which extends at one side of the machine and the grain is tied into bundles by binding mechanism usually located at the far side of the machine from the sickle bar. The object of the invention is to provide an 20 improved machine of this class, the improvements being especially concerned with the mechanism for carrying the loose grain from the sickle bar to the binding mechanism.

In the accompanying drawings;

25 Figure 1 is a detail plan view of a harvesting machine embodying the features of improvement provided by the invention, some of the parts being broken away and other parts being shown in section;

30 Fig. 2 is a rear elevation of the machine, Fig. 3 is a transverse sectional view, the sectional plane being indicated by the line 3—3 on Fig. 1.

Fig. 4 is a detail front elevation of the 35 machine showing some of the parts of the driving mechanism;

Fig. 5 is a detail plan sectional view taken on the line 5—5 of Fig. 4;

Fig. 6 is a detail transverse section taken 40 on the line 6—6 of Fig. 5;

Fig. 7 is a detail transverse section taken on the line 7—7 of Fig. 1;

Figs. 8 and 9 are detail perspective views 45 showing elements of two different conveyer mechanisms;

Figs. 10 and 11 are detail sectional views taken on the lines 10—10 and 11—11 respectively of Fig. 3, and

Fig. 12 is a detail perspective view showing 50 some of the elements of another conveyer mechanism.

While the drawings illustrate a machine of the general type shown in Patent No. 1,177,104 issued to me March 28, 1916 for a 55 harvesting machine, some of the features of the present invention are not limited in their

application to machines of this type. If desired, the invention may be so employed as to completely avoid the use of any canvas apron or other form of fabric conveyer in a 60 reaper and binder.

The sickle bar 15 (Figs. 1 and 7) extends along the forward edge of the grain platform 16 as usual. The binder mechanism may be of a well known form comprising 65 the oscillating needle arm 17 (Fig. 3). As shown, this mechanism operates to tie the grain into bundles upon an inclined flat deck 18 which extends upwardly away from the inner edge of the platform 16, the binder 70 mechanism being located adjacent the remote edge of the said deck. The usual trip finger against which the grain is packed to form a bundle and which is moved by a pre-determined pressure of the grain against the 75 same, is indicated at 19.

In carrying out the present invention the upper surface of the grain platform 16 preferably comprises a series of transversely extending fixed sheet metal plates 20 in strip form, and front and rear marginal angle plates 21, all of which are spaced apart to provide intervening slots 22, through which project the traveling fingers 23 of a platform conveyer. The conveyer fingers 23 85 are carried by bars 24 arranged transversely with respect to the length of the slots 22 below the sheet metal plates 20. The bars 24 are in turn carried by a pair of endless sprocket chains 25, one adjacent the forward 90 edge of the platform 16 and the other adjacent the rear edge of the platform (Fig. 1).

The two sprocket chains 25 turn over shafts 26 and 27 journaled in the platform frame, one adjacent each end of the platform. Preferably the shaft 27 extends both 95 in front and in rear of the platform 16 and is provided with driving sprockets 28 and 29, (Figs. 2 and 3) at its opposite ends.

While the conveyer fingers 23 are desirably made yielding, each of these fingers is preferably firmly held by the corresponding bar 24. As shown, each conveyer finger 23 comprises a length of resilient wire, part of which is formed into a coil 30 (Fig. 9) about 100 the bar 24 and one end of the wire is anchored to the bar, as by being extended through a clip 31, fixed upon the bar. On the other hand, the bars are rotatably held by the sprocket chains 25. As shown, each 110 bar 24 extends through and is journaled in one of the links, as 32, (Fig. 9) of each of

the sprocket chains 25. To prevent rotation of the bars 24 during the travel of the corresponding fingers 23 along the slots 22, each bar may be provided with backwardly turned ends 33 forming cranks which travel in ways 34 (Fig. 7) conveniently formed by securing other angle plates 35 against the angle plates 21 upon the inside. As the angle plates 35 preferably extend only between the shafts 26, 27 and are formed with down turned ends, as 36, (Fig. 3), each bar 24 is permitted to rotate as it turns about the shafts 27. The corresponding conveyer finger is thus drawn downwardly out of the grain, without any tendency to break the straw or interfere with the travel of the grain in any manner.

While the conveyer fingers 23 leave the grain as it reaches the inner end of the platform 16, movement of the grain onto the inclined deck 18 (Fig. 3) is readily accomplished by the provision of an intermediate conveyer mechanism generally designated 37 and hereinafter referred to as the picker. As shown, the picker 37 is located above the inner end of the platform and extends over the adjacent part of the deck. If desired, the picker may comprise conveyer fingers 38, bars 39 and sprocket chains 40, all constructed and connected in the same manner as the corresponding parts of the platform conveyer except that the conveyer fingers 38 of the picker are proportionately much longer and preferably of such length as to dip into grooves 41 (Figs. 1 and 11) formed in the top plates 20 of the platform.

The two sprocket chains 40 of the picker 37 turn about shafts 42, 43 (Fig. 3), suitably journaled in the frame of the machine 40 and one of which, as 43, is driven through a sprocket chain 44 from the sprocket wheel 29 on the forward end of the shaft 27. Rotation of the bars 39 of the picker may be uncontrolled except during downward movement of the bars in rear of the shaft 42 and forward movement of the bars over the adjacent part of the platform 16 and deck 18. As shown, a pair of guide plates as 45, 46, (Figs. 3 and 11) suitably held 45 upon the frame of the machine at each side of the picker, slidingly receive the adjacent crank end, as 47, (Fig. 12) of each bar 39 between them during that part of the movement of the bar when its rotation is to be 50 controlled. By this means the conveyer fingers 38 of the picker are swung downwardly and forwardly during the travel of the bars 39 about the shaft 42 and these fingers are held in substantially upright positions 55 while they travel forwardly over the adjacent portions of the platform 16 and deck 18. On the other hand, as rotation of the picker bars 39 is not controlled while these bars turn about the shaft 43, the fingers 38 are gently lifted out of the advanc- 60 65

ing grain as they approach the limit of their forward travel. To insure that none of the grain will become entangled with the bars 39 or sprocket chains 40, of the picker, a plurality of guard straps 37' in bail form, 70 extend about the ends of the picker and under the path of the bars 39 between the several fingers 38.

In the form of construction illustrated in the drawings, another endless conveyer, 75 generally designated 48 and hereinafter referred to as the packer, is employed for continuing the movement of the grain over the inclined deck 18 and packing it against the trip finger 19 (Fig. 3) for the formation of 80 the bundles. While the operative parts of the packer 48 are principally located below the deck, the mechanism includes traveling packer fingers 49 which project through slots 50 in the deck during their forward 85 movement. The packer also includes a pair of sprocket chains 51 and a series of transverse bars 52 which are carried by and connect the sprocket chains 51 at intervals. The bars 52 carry the packer fingers 49 and 90 the two sprocket chains 51 each turn over a pair of sprocket wheels 53, 54.

In the packer 48, the tilting of the fingers, as 49, to permit them to be gently withdrawn from the grain as they recede 95 through the deck is accommodated by rotatably mounting these fingers upon the bars 52. As most clearly shown in Fig. 8, each finger 49 is formed from a length of wire which is doubled at its mid-length and 100 its two parts wrapped around the corresponding bar 52 with the ends of the wire projecting beyond the same to provide a pair of guide arms 55. Associated with each chain 51 are a pair of angle bars 56 105 with which the guide arms 55 are slidingly engaged during the forward travel of the corresponding finger 49.

As the packer 48 must partake of the movement of the needle arm 17 incident to the adjustment of the machine for operation upon grain of different lengths, the sprocket wheels 53, 54, the needle arm, guides 56 and the portion of the table provided with slots 50 and the slot for the needle arm, are preferably all mounted for axial movement. For this purpose, the sprocket wheels 54 are slidingly mounted upon a bar 57 which extends in the direction of the length of the machine. The sprocket wheels 53, on the other hand, are located upon the packer shaft, as 58. Inasmuch, however, as the packer shaft 58 is continuously driven, as usual, while when the form of packer 48 shown is used it is preferred that its movement should be interrupted during the tying of each bundle of grain, the sprocket wheels 53 are not rotatably connected with the shaft 58 but are mounted upon a sleeve 59 which incloses the said 130

shaft. The angle bars 56 are supported at their opposite ends upon the bar 57 and sleeve 59.

5 Interruption of the packer, as 48, during the tying of each bundle of grain, may be accomplished if the sleeve 59 is driven from the packer shaft 58 through a form of clutch mechanism which is most clearly illustrated in Figs. 4, 5 and 6. As shown, 10 the packer shaft 58 carries a driving member 60 which is fixed upon the said shaft and is formed with a pair of axially projecting driving lugs 61, one at each side of the shaft. The sleeve 59, on the other hand, 15 carries a clutch plate 62 and a tilting contact member 63 is pivotally secured to the plate 62, as at 64 (Fig. 6). The contact member 63 is formed with a laterally projecting lug 65 and a spring 63' reacts between the clutch plate 62 and contact member 63 to normally support the contact member 63 in such a position that the lug 65 extends into the path of movement of the driving lugs 61. As the packer shaft 58 20 rotates continuously in the direction indicated by the arrow on Fig. 6, engagement of either one of the driving lugs 61 with the lug 65 of the contact member 63 serves to drive the sleeve 59 and this condition 25 is maintained except during the tying of each bundle of grain.

When the bundle forming mechanism is set in motion, rotation of the sleeve 59 is arrested by swinging the contact member 30 63 upon its pivot 64 to move the lug 65 out of the path of the driving lugs 61. This is conveniently accomplished by throwing a stop lug 66 into the path of an outwardly projecting part 67 of the tilting contact member 63. As shown, the stop lug 66 is formed upon one of the crank arms 68 of a rock shaft 69. A spring 70, coiled about the shaft 69, acts to turn this shaft in the direction to throw the stop lug 66 into the 35 path of the part 67 but the shaft is normally held against this spring actuated movement by contact of another crank arm 71 of the rock shaft 69 with a part of the bundle forming mechanism.

40 Referring more particularly to Fig. 4, the crank arm 71 rises from the forward end of the rock shaft 69 and is turned laterally at its upper end for engagement with the crank arm 72 which actuates the needle arm 17, in the position of rest of the last 45 mentioned crank arm.

When the bundle forming mechanism is set in motion, the crank arm 72 moves upwardly away from the upper end of the 50 crank arm 71 (Fig. 4) and the rock shaft 69 is turned by its spring 70 to throw the stop lug 66 (Fig. 6) into the path of the projecting part 67 of the contact member 63. The contact member 63 is thereby 55 tilted on its pivot 64 to move the lug 65

out of the path of the driving lugs 61. Movement of the sleeve 59 and packer fingers 49 is thereby arrested although the packer shaft 58 continues in motion and is relied upon to drive the bundle ejector arm 70 73 and needle arm 17 through the clutch 74 and beveled gear 75, as usual. As the crank arm 72 approaches the position of rest illustrated in Fig. 4, it again engages the upper end of the crank arm 71. The 75 rock shaft 69 is thereby turned against the effort of the spring 70 to throw the stop lug 66 out of the path of the part 67 (Fig. 6). Tilting of the contact member 63 by the spring 66 is thereby permitted, thus 80 throwing the lug 65 into the path of the driving lugs 61 for actuating the sleeve 59 and packer fingers 49.

It will be understood that the crank arm 72 is mounted upon the forward end of a 85 rock shaft 76 which also carries the needle arm 17, (Fig. 3) and that the clutch 74 is operated by movement of the trip finger 19, as usual. Furthermore, all of the operative parts referred to herein are driven 90 from a longitudinal driving shaft 77 (Fig. 2). As shown, the drive shaft 77 carries a sprocket wheel 78 upon its rear end and a sprocket chain 79 which turns about this 95 wheel also turns about the sprocket wheel 28 on the rear end of the platform conveyer drive shaft 27 and about a sprocket wheel 80 on the rear end of the packer shaft 58. The sickle bar 15 is driven as usual by a crank (not shown) on the forward end 100 of the shaft 77.

I claim as my invention:

1. In a harvesting machine, in combination, a transversely slotted platform, a sickle bar in front of the platform, a flat deck extending away from the platform at one side of the same, bundle forming mechanism at the remote side of the deck from the platform, and three sets of traveling conveyer fingers all movable toward the said bundle forming mechanism, one set of the said conveyer fingers being supported below the platform and operating through its slots, another set of the said conveyer fingers being supported above the deck and operating over a part of the same adjacent the platform and over a portion of the platform, their path of movement overlapping that of the first named set, and the third set of conveyer fingers being supported below the deck 110 and operating through the same adjacent the said bundle forming mechanism and acting as packers.

2. In a harvesting machine, in combination, a transversely slotted platform, a sickle bar in front of the platform, a flat deck extending away from the platform at one side of the same, intermittently operable bundle forming mechanism at the remote side of the deck from the platform, three sets of travel- 125

130

ing conveyer fingers all movable toward the said bundle forming mechanism, one set of the said conveyer fingers being supported below the platform and operating through 5 its slots, another set of the said conveyer fingers being supported above the deck and operating over a part of the same adjacent the platform and over a portion of the platform, their path of movement overlapping 10 that of the first named set, and the third set of conveyer fingers being supported below the deck and operating through the same adjacent the said bundle forming mechanism and acting as packers, and 15 means for interrupting the operation of the last mentioned set of conveyer fingers during the operation of the said bundle forming mechanism.

3. In a harvesting machine, in combination, 20 a platform having a transversely slotted top, a sickle bar in front of the platform, a binder deck extending away from the platform at one side of the same, a shaft extending along each side of the platform 25 below its said slotted top, a set of conveyer chains turning about the shafts, the upper lengths of the chains moving toward the said binder deck, swinging picker fingers carried by the chains in line with the slots 30 of the top of the platform and means for holding the picker fingers against swinging in upright position during their movement along the slots toward the binder deck, the

said fingers being free to swing during their movement about the shaft which is at that 35 side of the platform adjacent the binder deck.

4. In a harvesting machine, in combination, a binder deck, a continuously rotating shaft extending under the said deck, a sleeve 40 mounted upon the shaft, a clutch operatively connecting the sleeve and shaft, packers driven by the sleeve, bundle forming mechanism, operative connection between the shaft and bundle forming mechanism including a 45 clutch, a trip operated by pressure of grain delivered by the packers controlling the last mentioned clutch, and means operated by the bundle forming mechanism controlling the first mentioned clutch. 50

5. In a harvesting machine, in combination, bundle forming mechanism, a continuously operating shaft, an arm with a stud thereon rotating with said shaft, a sleeve loosely mounted on said shaft, packer conveyer operating sprocket wheels mounted on 55 said sleeve, an arm projecting from said sleeve, a latch pivoted to said arm spring pressed into the path of rotation of said stud and means set into operation by initial movement of said mechanism for removing said latch from the path of said stud during 60 operation of said mechanism whereby the packer conveyer will not operate while said mechanism is operating. 55

WALTER L. HENDRICKS.
